UNITED STATES PATENT OFFICE.

GEORGE M. HOPKINS AND I. NEWTON HOPKINS, OF BROOKLYN, ASSIGNEES
TO THE ECONOMIC MOTOR COMPANY, OF NEW YORK, N. Y.

GAS-ENGINE.

SPECIFICATION forming part of Letters Patent No. 284,851, dated September 11, 1883.

Application filed May 24, 1883. (No model.)

To all whom it may concern:

Be it known that we, GEORGE M. HOPKINS and I. NEWTON HOPKINS, both of Brooklyn, in the county of Kings and State of New York, 5 have invented certain new and useful Improvements in Gas-Engines, of which the following is a full, clear, and exact description.

Our invention consists in a double pendent valve for covering the ignition-opening, one 10 part of the valve being perforated and covered by the other; also, in the combination, with the ignition-valve of a gas-engine, of an igniting-burner having a flared mouth, and provided with an inclined deflector for spreading 15 the flame over the ignition-valve; also, in the combination, with the burner, of a perforated protector for shielding the igniting-flame from blasts of air.

Reference is to be had to the accompanying 20 drawings, in which Figure 1 is a side elevation of the cylinder of a gas-engine, partly in section. Fig. 2 is a front elevation of the explosion-valve and igniting-burner. Figs. 3 and 25 4 show the parts of the double explosion-valve. Fig. 5 is a rear elevation of the air-supply valve.

Like parts are designated by the same letters of reference in the different figures of the drawings.

Over an opening, A, in the side of the cylinder B is secured the plate C, having the inclined inner surface, *a*, and conical ignition-aperture *b*. In the opening A and over the aperture *b* are suspended two flap-valves, *c* *d*, from the screw *e*, forming the common support 35 of both valves. The valve *d* is longer than the valve *c*, and is perforated with a small hole, *f*, opposite the center of the ignition-aperture *b*. This construction insures a division of the igniting-flame as it enters the cylinder, and secures regular and quiet explosions. This device, which we call the "ignition-valve," is provided with a protector, *D*, of wire-gauze or perforated sheet metal, which is attached to the plate C near the top, and 45 extends downward below the ignition-valve, leaving a space, in which is placed the upper end of the igniting-burner E. The burner E is of the class known as the "Bunsen burner." Its upper end is made wide and flat, with its

longer diameter parallel with the face of the ignition-valve. Attached to the upper end of the burner is a curved deflector, *g*, which is inclined outward, and spreads the flame so as to cover more or less of the face of the ignition-valve. The deflector *g*, besides spreading the flame, also prevents the flame from being blown out by any blasts from the ignition-valve by receiving such blasts on its back and directing them away from the flame.

To insure an equal supply of air and gas to the engine-cylinder, we have provided the improved air-valve F and the gas-equalizing reservoir G. The valve F is provided with the ordinary openings, *h*, for the admission of air, and with a flexible valve, *i*, covering the said openings. The valve *i* is held in place by the head of a tubular screw, *j*, passing through the seat of the valve *i*. A metal ring, *k*, placed against the back of the valve *i*, is pressed by a bow-spring, *l*, connected with the end of the adjusting-screw *m* by a swivel-joint. The adjusting-screw *m* is fitted to an internal thread in the tubular screw *j*, and is provided with a milled head. By turning the screw *m* in or out the pressure of the valve *i* upon its seat 75 may be varied, and thus the supply of air can be regulated.

A sheet-metal reservoir, G, is connected with the gas-supply pipe *n* and gas-regulating valve *o*, the said valve *o* being in communication 80 with the gas-check valve *p*, through which gas is drawn into the cylinder B. The gas-reservoir G may be employed without any filling; but we have found by experiment that gas may be economized to some extent by filling the reservoir G with wool, hair, or other fibrous material, and when it is thus filled a strainer, *q*, is placed over the discharge-opening of the reservoir to prevent the escape of the filling.

Having thus described our invention, we 90 claim as new and desire to secure by Letters Patent—

1. In a gas-engine, the plate C, having the conical opening *b*, the valve *d*, provided with the aperture *f*, and the valve *c*, in combination, substantially as herein shown and described.

2. In a gas-engine, an igniting-burner con-

sisting of a Bunsen burner, E, having a flared mouth, and provided with the inclined deflector *g*, in combination with the ignition-valve, as herein specified.

5. In a gas-engine, the burner E, having the deflector *g* and the perforated protector D, in combination with the ignition-valve, as specified.

4. The igniting-burner E, having a flared

mouth, the inclined deflector *g*, and the perforated protector D, in combination with the ignition-valve of a gas-engine, as herein specified.

GEO. M. HOPKINS.
I. NEWTON HOPKINS.
